(57) **CLAIM**

The ornamental design for a jewelry case as shown and described.

DESCRIPTION

FIG. 1 is a front perspective view of a first embodiment of a jewelry case of my design.

FIG. 2 is a rear perspective view of the jewelry case of FIG. 1.

FIG. 3 is a front view of the jewelry case of FIG. 1.

FIG. 4 is a back view of the jewelry case of FIG. 1.

FIG. 5 is a first side view of the jewelry case of FIG. 1.

FIG. 6 is a second side view of the jewelry case of FIG. 1.

FIG. 7 is a top view of the jewelry case of FIG. 1.

FIG. 8 is a bottom view of the jewelry case of FIG. 1.

FIG. 9 is a front perspective view of a second embodiment of a jewelry case of my design.

FIG. 10 is a rear perspective view of the jewelry case of FIG. 9.

FIG. 11 is a front view of the jewelry case of FIG. 9.

FIG. 12 is a back view of the jewelry case of FIG. 9.

FIG. 13 is a first side view of the jewelry case of FIG. 9.

FIG. 14 is a second side view of the jewelry case of FIG. 9.

FIG. 15 is a top view of the jewelry case of FIG. 9.

FIG. 16 is a bottom view of the jewelry case of FIG. 9.

FIG. 17 is a front perspective view of a third embodiment of a jewelry case of my design.

FIG. 18 is a rear perspective view of the jewelry case of FIG. 17.

FIG. 19 is a front view of the jewelry case of FIG. 17.

FIG. 20 is a back view of the jewelry case of FIG. 17.

FIG. 21 is a first side view of the jewelry case of FIG. 17.

FIG. 22 is a second side view of the jewelry case of FIG. 17.

FIG. 23 is a top view of the jewelry case of FIG. 17.

FIG. 24 is a bottom view of the jewelry case of FIG. 17.

FIG. 25 is a front perspective view of a fourth embodiment of a jewelry case of my design.

FIG. 26 is a rear perspective view of the jewelry case of FIG. 25.

FIG. 27 is a front view of the jewelry case of FIG. 25.

FIG. 28 is a back view of the jewelry case of FIG. 25.

FIG. 29 is a first side view of the jewelry case of FIG. 25.

FIG. 30 is a second side view of the jewelry case of FIG. 25.

(Continued)

FIG. 31 is a top view of the jewelry case of FIG. 25; and, FIG. 32 is a bottom view of the jewelry case of FIG. 25. The dash-dash-dash type broken lines shown in the drawings are included for the purposes of illustrating portions of the jewelry case and form no part of the claimed design.

The dot-dash-dot-dash type broken lines shown in the drawings define the boundaries of the claimed design. The appearance of any portion of the jewelry case between the dot-dash-dot-dash type broken lines forms no part of the claimed design.

Randomly dashed lines represent surface shading.

1 Claim, 28 Drawing Sheets
